Primary Examiner—Gary D. Watson

Attorney, Agent, or Firm—Ladas & Parry

[57] CLAIM

The ornamental design for chair, as shown and described.

DESCRIPTION

FIG. 1 is a perspective view of chair showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a second embodiment of that shown in FIG. 1;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines shown on the seat and backrest in the first embodiment are understood to represent stitching.
